(57) **CLAIM**

The ornamental design for a hat and coat hook for over the door and surface mounting, as shown and described.

DESCRIPTION

FIG. 1 is a perspective view of a hat and coat hook for over the door and surface mounting showing our new design;

FIG. 2 is a top plan view thereof;

FIG. 3 is a front elevational view thereof;

FIG. 4 is a right side elevational view thereof, the left side elevational view being a mirror image;

FIG. 5 is a rear elevational view thereof;

FIG. 6 is a bottom plan view thereof;

FIG. 7 is a perspective view of a second embodiment of the design shown in FIG. 1;

FIG. 8 is a top plan view thereof;

FIG. 9 is a front elevational view thereof;

FIG. 10 is a bottom plan view thereof;

FIG. 11 is a rear elevational view thereof;

FIG. 12 is a right side elevational view thereof;

FIG. 13 is an alternate environmental view of the design shown in FIG. 7; and,

FIG. 14 is a third embodiment of the design shown in FIG. 1. The dotted-line showing in the drawings illustrates environmental matter and forms no part of the claimed design.
